Des. 204,540
Patented Apr. 26, 1966

204,540

VACUUM CLEANER SUPPORT OR SIMILAR ARTICLE

Thomas R. Symington, 333 E. 53rd St., New York, N.Y.

Filed Aug. 25, 1965, Ser. No. 86,713

Term of patent 14 years

(Cl. D9—2)

FIGURE 1 is a front elevational view of a vacuum cleaner support or similar article showing my new design;

I claim:

The ornamental design for a vacuum cleaner support or similar article, substantially as shown.
